COMBINATION CARTON AND DISPLAY BOX

Harold E. Downing, Chicago, Ill., and Thomas H. Vaughn, Tenafly, N.J., assignors to Gray Realty Corporation, Benlon Harbor, Mich., a corporation of Delaware

Filed Dec. 24, 1959, Ser. No. 58,806

Term of patent 7 years

(Cl. D58—12)

FIG. 1

Fig. 3

FIG. 1 is a front perspective view of a combination carton and display box showing our new design, and

FIG. 2 is a rear perspective view of the combination carton and display box shown in FIG. 1.

FIG. 3 is a front perspective view of the carton and display box depicting said carton and display box in a partially open position.

The side not shown is the same as the side shown. The top, bottom and sides are flat and plain in closed position.

We claim:

The ornamental design for a combination carton and display box, substantially as shown and described.
